UNITED STATES PATENT OFFICE

160,178

PARTY BASKET OR SIMILAR ARTICLE

Philip Klein, Maplewood, N. J.

Application May 21, 1949, Serial No. 2,798

Term of patent 3½ years

(Cl. D59—2)

To all whom it may concern:

Be it known that I, Philip Klein, a citizen of the United States, residing at Maplewood, in the county of Essex and State of New Jersey, have invented a new, original, and ornamental Design for a Party Basket or Similar Article, of which the following is a specification, reference being had to the accompanying drawing, forming part thereof.

In the drawing, the figure is a front perspective view of a party basket or similar article, showing my new design.

I claim:

The ornamental design for a party basket or similar article, as shown.

PHILIP KLEIN.
